ABSTRACT OF THE DISCLOSURE

Aromatic hydrocarbons are dealkylated in the presence of steam and a nickel-beryllium oxide catalyst having a nickel content of from 5 to 80 weight percent. The catalyst is prepared by impregnating basic beryllium carbonate, beryllium oxide, or beryllium hydroxide with an aqueous solution of a nickel compound such as nickel nitrate, drying the resulting product, calcining it at about 500° C. in a stream of inert gas, then pelletizing it, and reducing the resultant powder with hydrogen. The dealkylation is preferably carried out at a temperature of 350–500° C. The steam and aromatic hydrocarbon are respectively employed in a molar ratio of about 3–19 to 1. The dealkylation is preferably carried out a space velocity of about 1500 to 6000 hr.⁻¹ based on the total volume of steam and aromatic hydrocarbon vapor, and at a liquid hourly space velocity of the aromatic hydrocarbon of about 0.8 to 4.3. Surprisingly, dealkylation occurs with little disintegration of the benzene ring.

This invention relates to a process for the dealkylation of aromatic hydrocarbons. More particularly, the invention relates to a process for dealkylating aromatic hydrocarbons by use of a nickel-beryllium oxide catalyst in the presence of steam.

In the prior art processes for dealkylating aromatic hydrocarbons, it is commonly known that the dealkylation reactions are carried out thermally or catalytically in the presence of hydrogen to obtain, together with saturated hydrocarbons, aromatic hydrocarbons having carbon numbers less than those of the corresponding starting aromatic hydrocarbons. In addition to the above methods, dealkylation of aromatic hydrocarbons by use only of steam is known, but these prior art processes usually cause so remarkable disintegration of the aromatic ring that they are not carried out to the extent of one's satisfaction.

We have made an extensive research to find catalysts effective in such a dealkylation process wherein steam is used instead of expensive hydrogen. As the result, we have found that an aromatic hydrocarbon having one or more alkyl groups can be effectively dealkylated with the benzene nucleus mostly preserved in the presence of steam by using a nickel-beryllium oxide catalyst, while the splitted alkyl groups are converted mainly into carbon dioxide and hydrogen.

2

Aromatic hydrocarbons which are preferably used in the present invention include, for example, toluene, o-, m-, and p-xylanes, ethylbenzene, cumene and methyl-naphthalen. These may be used either singly or in the form of mixtures.

The catalyst employed in the present invention is prepared in such a manner that basic beryllium carbonate is impregnated with an aqueous nickel nitrate solution, dried and calcined at about 500° C. in the stream of an inert gas such as nitrogen to obtain a powder, which is then pelletized and reduced with hydrogen. As a beryllium source for the catalyst preparation, beryllium oxide or beryllium hydroxide may also be employed instead of basic beryllium carbonate, and the nickel source is not limited to nickel nitrate only.

Thus, the catalyst used in the present invention is composed substantially of nickel and beryllium oxide. The nickel content of the catalyst may range from 5 to 80 weight percent.

The dealkylation reaction of the present invention is desirably effected at about 350° to 500° C. at atmospheric pressure or under an increased pressure. In the reaction, the space velocity is preferably about 1,500 to 6,000 hr.⁻¹ based on the total volume of the starting steam and the starting aromatic hydrocarbon vapor, and the liquid hourly space velocity (L.H.S.V.) of the starting aromatic hydrocarbon is preferably about 0.8 to 4.3. Ordinarily, the molar ratio of the starting steam to the starting aromatic hydrocarbon is about 3–19 to 1.

The present invention is illustrated in further detail hereinbelow with reference to examples.

EXAMPLES 1–28

Preparation of catalyst:

A given amount of powder of a desired carbonate (or basic carbonate) was added to an aqueous solution containing a given amount of nickel nitrate. The mixture was heated gently on a water bath and evaporated to dryness.

Then, the resultant mixture of the carbonate and the nitrate was taken out, dried at about 100° C. and calcined at 450° C. for 2 hours in the stream of nitrogen to obtain a powder containing about 20 weight percent of nickel. The resultant powder was pelletized under a pressure of 4,000 kg./cm.². The pellets were crushed and sieved to grains of 1 to 2 mm. in size, which were then reduced for 2 hours with hydrogen at 350° to 450° C. in a dealkylation reaction tube.

Dealkylation reactions:

The aromatic hydrocarbons used as starting materials were toluene, ethylbenzene, o-, m-, and p-xylanes and cumene. The dealkylation reactions of these were individually effected at a temperature ranging from 347° to 450° C. and at atmospheric pressure, using a conventional flow type apparatus containing 5 ml. of the catalyst prepared in the above-mentioned method. The analyses of the product liquids and gases after the dealkylation reactions were carried out by a gas chromatographic method. The conditions and the results of the dealkylation reactions are shown in Table 1.

NOTE.—In Example 26, beryllium oxide was used as the beryllium source; in Example 27, beryllium hydroxide was used as the beryllium source; in Example 28, the calcination of catalyst was effected at 850° C.

Notes: In Example 26, beryllium oxide was used as the beryllium source. In Example 27, beryllium hydroxide was used as the beryllium source. In Example 28, the calcination of catalyst was effected at 850° C.

What we claim is:

1. A process for the dealkylation of an aromatic hydrocarbon, characterized in that the dealkylation is effected by use of a nickel-beryllium oxide catalyst in the presence of steam.

2. A process for the dealkylation of an aromatic hydrocarbon according to claim 1, wherein said dealkylation is carried out at a temperature of about 350° to 500° C. at atmospheric pressure or under an increased pressure.

3. A process for the dealkylation of an aromatic hydrocarbon according to claim 2, wherein said dealkylation is carried out at the space velocity of about 1500 to 6000 hr.⁻¹ based on the total volume of the starting steam and the starting aromatic hydrocarbon vapor and at the liquid hourly space velocity (L.H.S.V.) of the starting aromatic hydrocarbon of about 0.8 to 4.3.

4. A process for the dealkylation of an aromatic hydrocarbon according to claim 1, wherein said aromatic hydrocarbon is at least one member selected from the group consisting of toluene, o-, m- and p-xylanes, ethylbenzene, cumene and methyl naphthalene.

5. A process for the dealkylation of an aromatic hydrocarbon according to claim 1, wherein said nickel-beryllium oxide catalyst is that which is obtained by impregnating a beryllium compound selected from the group consisting of beryllium basic carbonate, beryllium hydroxide and beryllium oxide with an aqueous solution of a water-soluble nickel compound, drying the impregnated mass and calcining it at about 500° C. in the stream of an inert gas, forming the calcined product to suitable shape and then reducing it with hydrogen to have a catalyst substantially composed of nickel and beryllium oxide and having a nickel content of 5-80% by weight.
